VENTILATING LOUVERS FOR STORM
WINDOWS

Frederick P. Chelton, Baltimore, Md.

Application July 19, 1944, Serial No. 545,634

2 Claims. (Cl. 98—97)

1

This invention refers to windows and more particularly auxiliary sashes therefor. It has among its objects to provide an auxiliary frame that can be adapted for use with conventional windows to protect same against storms and weather, and if desired be opened in part to provide ventilation.

Other objects will become apparent as the invention is more fully set forth.

It is customary to make combination storm window frames and windows ventilatable by constructing the lower portion of the sash into a duplex type structure, that takes up a greater portion of the space suitable for glass and thereby interferes with the passage of useful light therethrough. This combination unit is independent of the main window and is placed on the outside of the building on which it is installed. In this invention, the unit is of combination type similarly but its frame is built with the ventilating feature within it away from the glass so it will not obstruct the same or be unduly conspicuous. The ventilation can be adjusted to suit. This feature also prevents the tendency of the window to fog under certain conditions to be controlled.

In the drawings is shown an example of a device of this nature, by way of illustration. This device embodies the principles of this invention, and its views in the drawings are as follows:

Figure 1 is a front elevation of the device embodying this invention;

Figure 2 is a side elevation in section taken along line 2—2 of Figure 1, and

Figure 3 is a rear elevation taken along line 3—3 of Figure 2.

Similar reference characters refer to similar parts throughout the drawings.

In the structure outlined, 1 represents a brick wall of the building which is built with an opening 2 in a conventional manner to take a conventional window frame 3. This frame has a pair of window sashes 4 moving in channels 5 to open and close in the usual manner. The counter-weights and other incidental features are also provided but not shown as they are well understood in the art. An additional frame structure 6 is formed to fit against the original frame on the outside of the wall. This is accomplished by making it with a horizontal head member 7, two vertical side members 8 and a base frame member 9. All the members are mortised into one another to make a strong frame and provided with holes 10 through which screws, nails or bolts can be used to fasten it to the frame 3. The bottom member 8 has an inset slot 11 cut longitudinally across

it, opening through the member to allow air to pass. The form of the slot is shown in the drawings. This slot is surmounted by double primary shutters 20 which are suitably hinged to permit their opening and closing in front of it, to control the passage of the air therethrough. The primary shutters 20 are appreciably larger in their total area, than the slot outside and are suspended to swing from their hinges 12 attached along their top sides, as indicated in the drawings. The shutters 20 are adjustable to various angles through the use of the flexible adjuster 13 which is attached at one end to the lower end of the lower shutter then passes through the hole 32 in the base frame member 9 and then passes through an eyelet stop member 26 attached to the horizontal runner 14. The shutters are opened from the inside when the flexible adjuster 13 is pushed outwardly and closed when it is pulled inwardly. The weight of the shutters will prevent the flexible adjuster from moving within the hole of its own accord on the outside and by the weight of the horizontal runner and eyelet stop member pressing down on the inside portion of the flexible adjuster 13. The variable positioning of the shutters 20 allow the air to be admitted to the inside of the storm sash and guides the air upwardly in back of said member in between it and the inner windows. Their position, as indicated enables them to spread across the outside of the slot opening 11 fully so as to offer little obstruction or interference with its functions of ventilating. The horizontal runner or supplementary shutter 14 has several features of value to the auxiliary window, particularly in preventing the carrying of dust collecting at the bottom of the frame on the rail portion 15, and acting as a guide for the air in its travel into the space between the windows. The runner as supplementary shutter is hinged at 18 and can be closed like a door into the slot in its rear inset 19. The supplementary shutter 14 is hinged at the bottom as shown on the lower inside face of the member 9 so it can open backwardly and attain a low horizontal position, and a vertical position when closed in the slot opening 11. A knob 26 mounted on the upper edge of the door that projects out sufficiently to engage the regular window sill so when the shutter 14 is opened wide and thereby limits its arcuate travel to the horizontal limit. The primary shutters 20 operate exteriorly to the storm window and overlap on each other with the upper one on top, as indicated in Figure 1. Any rain falling on the upper shutter 20 will slide down across its face and falling over the edge

will tend to miss the lower and under shutter 20, so that the rain will not leak through the joint between them, even if carried by a strong wind. The secondary shutter 14 can be adjusted to various angles in front of the air stream carried through the opening 11, to divert or allow it to flow horizontally through the original window in back of the storm window. This is accomplished by means of a bracket 13 which consists of a stiff wire suitably bent into a slight arc which passes through a hole or slot in the lower rail of the window frame and frictionally engages with the sides of the hole, so that it may be manipulated by the user inside the room, when the original window is opened for the purpose.

The window sashes 16 with their glass 17 are readily replaceable in the frame and may be substituted with fly screening if desired. They are fastened within the frame in any conventional manner 24, as long as they are removable.

When the conventional main window frame and window, and the auxiliary frame and window unit are in place, the owner opens or closes the shutters 20 positioned to close the single slot in the frame to control the passage of air therethrough by swinging them to the desired angle and fastening them in the selected location through the use of the flexible adjuster 13 which passes through the eyelet stop member 26 and frictionally holds the shutters 20 in the selected position. Their angular position prevents the rain and snow from getting in as they direct it away from the slot, and when they close on one another they overlap and prevent the passage of air and weather therethrough.

The lower portion of the upper auxiliary window is provided with metal strips 21 as indicated for strengthening and holding the sash in place when resting on stops 25, particularly when the lower one is being replaced.

While but one general form of the invention is shown in the drawings and described in the specifications, it is not desired to limit this application for patent to this particular form or in any other way otherwise than limited by the scope thereof, as it is appreciated that other forms of construction could be made that would use the same principles and come within the scope of the appended claims.

Having thus described the invention what is claimed is:

1. A storm window for adjustable and spaced placement in front of an original conventional window, comprising an outside frame having an upper rail and lower rail arranged for attachment to said original window, a window sash and glass removably attached to said frame, and positioned in front of the sash and glass of said original window, a crosspiece under the sash forming a support therefor and spaced above said bottom rail and forming an intervening opening between itself and the lower rail of the frame, a supplementary shutter hinged to said lower rail on

the interior surface of the frame and closable upwardly in a vertical position to close the opening and to arcuately travel downwardly on its hinges to a horizontal position to unobstruct said opening, and a pair of primary shutters hinged at their upper edges to swing from above and joined to operate together and adjustably close, said opening and overlapping the exterior face of the frame and cross piece opposite to said supplementary shutter and overlap each other so as to form an angular slide for rain striking them and guide same away from said opening.

2. A storm window for adjustable and spaced placement in front of an original conventional window, comprising an outside frame having an upper rail and lower rail arranged for attachment to said original window, a window sash and glass removably attached to said frame, and positioned in front of the sash and glass of said original window, a crosspiece under the sash forming a support therefor and spaced above said bottom rail and forming an intervening opening between itself and the lower rail of the frame, a supplementary shutter hinged to said lower rail on the interior surface of the frame and closable upwardly in a vertical position to close the opening and to arcuately travel downwardly on its hinges to a horizontal position to unobstruct said opening, and a pair of primary shutters hinged at their upper edges to swing from above and joined to operate together and adjustably close said opening and overlapping the exterior face of the frame and crosspiece opposite to said supplementary shutter and overlap each other so as to form an angular slide for rain striking them and guide same away from said opening, and a member passing through a hole in the lower rail of the window frame and frictionally engaging with the side of said hole so that the primary shutters may be opened and closed by the user from the inside of the room.

FREDERICK P. CHELTON.
